[57] CLAIM

The ornamental design for a network cable connector, as shown and described.

DESCRIPTION

FIG. 1 is a top perspective view of a network cable connector in accordance with our design, upper and lower sections of a connector system interfacing with the connector being shown in broken lines for illustrative purposes only;

FIG. 2 is a top plan view of the cable connector of FIG. 1;

FIG. 3 is a left side elevational view thereof;

FIG. 4 is a right side elevational view thereof;

FIG. 5 is a front elevational view thereof;

FIG. 6 is a rear elevational view thereof; and,

FIG. 7 is a bottom plan view thereof, contours of a connector interface being shown in broken lines for illustrative purposes only.

The broken line showing throughout the drawing figures is included for the purpose of illustrating environmental features and structure only, and forms no part of the claimed design.
